ROTARY DUPLICATING MACHINE

Alfred Marchev, La Grange, Ill., assignor to Ditto,
Incorporated, Chicago, Ill., a corporation of
West Virginia

Application October 11, 1935, Serial No. 44,523

4 Claims. (Cl. 101—132)

This invention relates to master sheet feeding for duplicating machines and is particularly adaptable to those machines of the type disclosed in the application of John W. Hernlund, Alfred 5 Marchev, and Robert F. Morrison, Serial No. 713,590, filed March 1, 1934, for Duplicators.

In machines of this character, the duplicating process is carried out rapidly. The master sheets used in the process are made with a 10 relatively soft carbon. In feeding the sheets to the gelatin band, care must be exercised to prevent the blurring of the soft carbon. The gripper fingers which normally grip and hold the sheets being fed to the drum in this type of machine 15 have been found to be capable of rubbing off some of the carbon thus causing a blurred master which in turn transfers its defects to the gelatin band. Also when copy sheets are fed to the drum, the carbon which has been rubbed off of the master sheet by the fingers and which may still adhere 20 to the fingers often sticks to the copy sheet and is transferred to the gelatin band by the copy sheet to further blur the impression on the gelatin band. It has been found necessary to relieve the pressure upon the master sheet as it is 25 advanced to the drum in such a fashion as to prevent this blurring taking place.

In the machine of the present invention, means 30 are provided whereby the operator of the machine may relieve the master sheet of any pressure from the sheet feeding mechanism that would tend to distort or blur the legend on the master sheet.

The machine also includes means of the aforementioned character which does not interfere 35 with the normal operation of the copy sheet paper stop and the guide plate and grippers which are necessary in accurately feeding copy sheets to the duplicating band.

The objects and features of the invention will 40 become more apparent from the following description reference being had to the accompanying drawings wherein—

Fig. 1 is a plan view of a portion of a duplicating machine showing the invention applied thereto;

Fig. 2 is a sectional view on the line 2—2 of Fig. 1;

Fig. 3 is a sectional view on the line 3—3 of Fig. 1;

Fig. 4 is a sectional view like Fig. 2 showing a changed position of the mechanism; and

Fig. 5 is a fragmentary sectional view on the line 5—5 of Fig. 1.

Referring now in detail to the drawings, the

duplicating machine to which the present invention is applied is of the system rotary type in which a rotary drum 10 is suitably mounted in a frame of which only one side piece 11 is shown in Fig. 1, the other side piece being shown for example in Fig. 3 at 12. The drum is suitably mounted upon a shaft 13 and is adapted to be rotated under the control of the operator by means of a motor 14 also mounted in the frame of the machine and connected to the drum 10 through suitable gearing indicated generally in Fig. 3 and suitable clutch mechanism not shown. The machine is provided with a feed table 15 which is mounted upon a carriage 16. The carriage 16 is pivoted to the casing by members 17 only one of which is shown, it being understood that there is a duplicate member at the opposite end of the carriage for mounting the carriage on the side frame members 11 and 12. The carriage is normally held in the position shown in the drawings by a latch 18 which engages a stud 19 on the side frame 11. The stud 19 is flattened at its free end as shown at 20 in Fig. 3 and is bevelled as shown at 21. The bevelled portion 21 engages the latch 18 while the flattened portion 20 serves as a resting place for a stop member 22 on the carriage.

Associated with the carriage there is a paper guide 23 supported upon suitable side frame members such as 24, it being understood that 30 there is another frame member similar to 24 at the opposite side of the machine. This frame member 24 is pivoted on a shaft 25 and has mounted thereon a roller 26 which is adapted to engage the top surface of one of a pair of end 35 frames 27 for the carriage. The shaft 25 also serves as a pivot for a paper gripper supporting arm 28 which at one end is connected by means of a spring 29 to a stud 30 on the end frame 27 of the carriage. At its other end, the arm 28 40 cooperating with a similar arm at the opposite side of the machine supports a paper gripper 31 which has a plurality of depending fingers 32 spaced from each other at their lower ends.

The gripper 31 is controlled by a cam and 45 roller mechanism which comprises an arm 33 secured to the shaft 25 and carrying at its free end a roller 34 that is adapted to engage a cam 35 mounted on the end of the drum 10. As the roller 34 rides up on the cam 35, it rocks the arm 50 33 and with it the shaft 25 to swing the paper gripper in a clockwise direction as shown in Figs. 2 and 4 whereby to move the paper grippers against a guide plate 36 which extends across the carriage and is fixed thereto by means of a 55

suitable bracket 37 and screws 38. The guide plate 36 is also cut away at its lower end to provide spaces, as indicated at 39, alternate with the fingers 32.

5 Beneath the paper guide 36 and the gripper 31, there is provided a margin bar 40 upon which the sheets fed through the chute formed by the grippers 31 and the guide plate 36 come to rest. This margin bar 40 is supported upon a shaft 41 10 by means of arms 42, shaft 41 being rotatably journaled in the end frames 27 of the carriage. The arm 42 also carries a stop projection at 43 adapted to engage a rectangular tie rod 44 which extends across the carriage to connect the end frames 27 thereof. Shaft 41 is normally urged 15 by a spring 45, which is secured thereto by a clamp 46, in such a direction as to hold the margin bar in the position shown in the drawings. The spring 45 is wound around the shaft 20 41 and has its free end secured to a pin 47 on the end frame 27 of the carriage so that rotation of the arm 42 in a clockwise direction to move the margin bar out of the way of the drum tightens the spring 45.

25 This movement of the margin bar just referred to is accomplished by means of an arm 48 fixed to the end of the shaft 41 on the outside of the end frame member 27 of the carriage and carrying a roller 49 for engagement with a margin bar 30 cam 50 also fixed to the end of the drum.

Functioning in conjunction with the gripper 31 and the guide plate 36 to hold sheets which are fed into the paper chute while the margin bar 40 is retracted, is a paper stop member 51 35 which has fingers 52 fitting between the fingers 32 of the gripper 31. This paper stop 51 is mounted on a shaft 53 which shaft projects through the end frame 27 of the carriage and has rotatably mounted thereon an arm 54 which 40 is provided with a roller 55 adapted to engage a paper stop lifting cam 56 also mounted on the end of the drum 10. There is also a second arm 57 fixed upon the shaft 53 and adapted to engage a pin 58 mounted upon the arm 54. The arm 57 45 is yieldingly held down against the pin 58 by means of a spring 59 which is secured to the end of the arm 57 and to a pin 60 on the end frame 27 of the carriage. As shown most clearly by Figs. 1 and 3, the shaft 53 also carries an arm 50 61 thereon which arm is extended out beyond the cam 56 and projects downwardly in line with a bar 62 which is fixed to a hand lever 63 pivoted on a tie rod 64 between the side frames 11 and 12 of the duplicating machine. The hand lever 55 63, when in the full line position shown in Fig. 3, does not extend into the path of the arm 61 so that, if the cam 56 is moved from beneath the roller 54, the arm 61 is free to rotate in a clockwise direction as shown in Fig. 3 and in a counterclockwise direction as shown in Fig. 2 to permit the spring 59 to swing the arm 57 and with it the shaft 53 in a direction to bring the paper stop 51 into the stop position illustrated in dotted lines in Fig. 2. However, if the lever 63 is moved 60 into the dotted line position shown in Fig. 3, the bar 62 is brought into position to engage the free end of the arm 61 so that, when the roller 55 moves off the cam 56, the arm 61 will prevent rotation of the shaft 53 and thus prevent the paper 65 stop 51 from moving into its sheet stopping or normal operating position.

In the normal operation of the machine, the paper stop 51 is desirably left free to assume its sheet intercepting or stopping position immediately upon the cam 56 moving out from under

the roller 55 so that a fresh copy sheet may be fed into the paper chute without waiting until the previous sheet has been completely withdrawn. The fingers 52 on the paper stop bear against the sheet being drawn out of the paper guide and pressed against the duplicating band by a platen roller 65 which is rotatably journaled in the carriage frame. This does no injury to a copy sheet, but is sufficient to blur or mar the legend in soft carbon upon a master sheet because it presses the master sheet against the fingers on the gripper 31. Therefore, when the master sheet is fed into the machine, the operator moves the lever 63 into the dotted line position shown in Fig. 3 to position the bar 62 10 in the path of the arm 61 so that he may hold the paper stop fingers 52 out of the paper chute until the master sheet is withdrawn, thereby preventing any pressure from being exerted upon the master sheet by the paper stop. 15

The lever 63 also functions to control the sheet stripping mechanism in a manner which will now be described. In duplicating machines of this character, the sheet stripping mechanism usually consists of a pair of stripping rolls 66 and 67 which are journaled in an auxiliary stripping frame 68 mounted upon the tie rod 69 which connects the two side frame members 11 and 12 of the duplicating machine. These two stripping rolls have the front edges of the sheets on the drum 10 directed into them by means of a stripping bar 70 which is carried upon a shaft 71 pivoted in the auxiliary frame 68. This shaft 71 also carries an arm 72 which is provided with a roller 73 adapted to engage a stripping control cam 74 25 also mounted on the end of the drum 10. The arm 72 has a fork 75 projecting upwardly therefrom which fork is provided with a pin 76. The lever 63 at its lower end is connected to a link 77 which link at its other end is connected to an arm 78 which is pivoted on a stub shaft 78' mounted in the side frame 11 of the machine. The arm 78 has a stop means thereon limiting its movement in a counterclockwise direction as shown in Fig. 3. This stop means consists of a screw bolt 79 which screws into an enlargement 80 provided on the arm 78 and is held in adjusted position by a lock nut 81. The head of the screw bolt 79 is adapted to engage a projection 82 on the end frame 11 of the machine. The link 77, 30 as shown most clearly in Fig. 1, is provided with an L-shaped bar 83 riveted thereto adjacent the connection of the link 77 with the arm 78 and projecting out into alignment with the pin 76. 35

Now, when the lever 63 is moved into the dotted line position shown in Fig. 3, this L-shaped bar 83 engages the pin 76 and prevents the roller 73 from moving toward the drum axis when it moves off its cam 74 so that the stripper bar 70 is not permitted to extend into the hollow part of the drum and direct a sheet on the drum to the stripping rollers. This permits the operator to maintain a master or a copy sheet up on the drum as long as he desires. The stripper bar 70 is urged toward the drum by a spring 70' in a 40 manner similar to that shown in the prior application hereinbefore mentioned. 45

From the above description, it is believed that the construction and operation of this device will be readily apparent to those skilled in this art. 50 While one embodiment of the invention has been shown and described, it is to be understood that it is capable of many modifications. Changes, therefore, in the construction and arrangement may be made without departing from the spirit 55 60 65 70 75 80 85 90 95 100

and scope of the invention as disclosed in the appended claims in which it is the intention to claim all novelty inherent in the invention as broadly as possible in view of the prior art.

5 The invention having thus been described, what is claimed as new and desired to be secured by Letters Patent is:

1. In a duplicating machine having a duplicating drum, means to rotate said drum, a paper feed chute for feeding sheets to said drum, and stripping means for stripping sheets from said drum, paper stop means normally extending across said chute to block passage of sheets through said chute, means for temporarily retracting said 10 paper stop means during rotation of said drum to permit feeding of a sheet through said chute, and means to hold said paper stop means in retracted position after its release by said retracting means.
2. In a duplicating machine having a duplicating drum, means to rotate said drum, a paper feed chute for feeding sheets to said drum, and stripping means for stripping sheets from said drum, paper stop means normally extending across said 15 chute to block passage of sheets through said chute, means for temporarily retracting said paper stop means during rotation of said drum to permit feeding of a sheet through said chute, means to hold said paper stop means in retracted position after its release by said retracting means.
3. In a duplicating machine having a duplicating drum, means to rotate said drum, a paper feed chute for feeding sheets to said drum, and stripping means for stripping sheets from said drum, paper stop means normally extending across said 20 chute to block passage of sheets through said chute, a spring holding said stop means in its normal position, means for temporarily retracting said paper stop means during 25 rotation of said drum to permit feeding of a sheet through said chute, and means to hold said paper stop means in retracted position after its release by said retracting means.

means to render said stripping means functionally inoperative, and a lever controlling said holding means and said last named means.

3. In a duplicating machine having a duplicating drum, means to rotate said drum, a paper feed chute for feeding sheets to said drum, and stripping means for stripping sheets from said drum, paper stop means normally extending across said chute to block passage of sheets through said chute, means for temporarily retracting said 10 paper stop means during rotation of said drum to permit feeding of a sheet through said chute, and means to hold said paper stop means in retracted position after its release by said retracting means, comprising an arm on said stop means 15 and a manually operable latch for said arm.

4. In a duplicating machine having a duplicating drum, means to rotate said drum, a paper feed chute for feeding sheets to said drum, and stripping means for stripping sheets from said drum, paper stop means normally extending across said 20 chute to block passage of sheets through said chute, a spring holding said stop means in its normal position, means for temporarily retracting said paper stop means during 25 rotation of said drum to permit feeding of a sheet through said chute, and means to hold said paper stop means in retracted position after its release by said retracting means.

ALFRED MARCHEV. 30
